H. HAUGH.
ADJUSTABLE MOUNTING BOARD.
FILED JAN. 30, 1922.

BY
Elmer B. Haugh
ATTORNEY.

ATTORNEY.

UNITED STATES PATENT OFFICE.

HARRY HAUGH, OF ANDERSON, INDIANA.

ADJUSTABLE MOUNTING BOARD.

Application filed January 30, 1922. Serial No. 532,743.

To all whom it may concern:

Be it known that I, HARRY HAUGH, a citizen of the United States, residing at Anderson, in the county of Madison and State 5 of Indiana, have invented certain new and useful Improvements in Adjustable Mounting Boards, of which the following is a specification.

This invention relates to adjustable 10 mounting boards, and is used for assembling tile blocks in preparation for attaching strips of retaining cloth, or paper, for holding the blocks of tile in assembled formation and ready to be laid. The prime feature of 15 the invention is the provision of means, in conjunction with the usual form of mounting board, for preventing assembling of blocks at certain points thereon while one color of blocks is being positioned.

20 A further feature of the invention is in so constructing the device that any number of the spaces on the board may be held unoccupied during the different operations of assembling the blocks on the board.

25 And a further feature of the invention is in so constructing the means for preventing the assemblage of blocks at prescribed points that it may be easily and quickly separated from the mounting board proper, 30 thus leaving all of the spaces of the mounting board free to receive the blocks of tile.

Other objects and advantages will be hereinafter more fully set forth and pointed out in the accompanying specification.

35 In the accompanying drawings, which are made a part of this application,

Figure 1 is a plan view of a number of tile blocks assembled ready to be applied to use, each alternate block being of a different 40 color from the other block.

Figure 2 is an edge elevation thereof,

Figure 3 is a top plan view of a portion of an adjustable mounting board showing the blocks of one color in assembled position and the means for preventing the assemblage of blocks in other sections of the board,

Figure 4 is a sectional view as seen on line 4—4, Figure 3,

50 Figure 5 is a view similar to Figure 3 showing all of the blocks in assembled position,

Figure 6 is a sectional view as seen on line 6—6, Figure 5, and

55 Figure 7 is a top plan view of a portion of the adjustable mounting board prior to

the assemblage of blocks thereon, and with means to prevent the assemblage of blocks in each alternate space on the board.

Referring to the drawings, 1 indicates 60 blocks of tile, such as are used for laying floors, wainscoting, and other purposes, and may be of any suitable size and shape and assembled together to form any desired configuration, such configurations being produced by using blocks of various colors.

In preparing blocks of this nature for use, they are preferably assembled in strips in the same relation that they will occupy when applied to use, and in retaining the 70 blocks in their various arranged positions they are first assembled and strips of fabric, or other substance, placed thereover and secured thereto with any suitable adhesive.

75 In assembling blocks of this nature, a mounting board 2 is provided, the surface of which is formed into a plurality of pockets 3 by arranging strips of metal 4 longitudinally of the board and subdividing the face of 80 the board by transversely extending strips 5, the strips being arranged in accordance with the configuration of the edges of the blocks being assembled, which, in the present instance, are in the form of squares, although 85 it will be understood that these pockets may be arranged in any suitable outline. Beads 6 are arranged around the edges of the board 2 which are of a height equal to the height of the blocks being assembled on the 90 board, while the strips 4 and 5 are of a less height than the height of the beads.

95 In assembling the blocks in strips, the number of blocks to be assembled are placed over the face of the board and the board then agitated until the blocks are all seated within the pockets, and as floors, and the like, built up of these blocks are usually built up in varying colors and configurations it is necessary to leave certain of the pockets unoccupied, so that blocks of different colors may be entered in these particular pockets. To this end, an auxiliary board 7 is provided, in one face of which are formed a plurality of sockets 8 for the reception of 105 pins 9, there being spaces provided for forming the same number of pins as there are pockets on the main board 2. The pins 9 are adapted to extend upwardly through openings 10 formed at the center of each 110 pocket and when entered through the board 2 will extend even with the top edges of the

bead 6, consequently it will be impossible for a block to enter the pocket through which a pin extends and all of the spaces occupied by pins will be held free of blocks, and a pin 5 may be entered through any particular pocket, or any particular pocket may be left free for the assemblage of a block by removing a pin from the auxiliary board 7.

In applying the device to use, supposing 10 each alternate pocket is to receive a white block and each alternate pocket a block of a different color, a sufficient number of pins are engaged with the auxiliary board 7 to extend through each alternate pocket on the 15 main board 2, and the pins are caused to enter the pockets by positioning the board 2 above the auxiliary board and then lowering the main board 2 until it rests on the upper face of the auxiliary board, such pins as are 20 engaged with the auxiliary board passing through the openings 10 with which they register.

A sufficient number of blocks of one color is then placed on the main board and the 25 board then agitated until the blocks have been properly seated in the unoccupied pockets, which, as shown in the drawings, will be each alternate pocket. After these 30 blocks are properly seated in their respective pockets the main board 2 is lifted from the auxiliary board thereby removing the pins from the remainder of the pockets, or, if desired the pins may be individually removed by pulling upwardly on the pins. 35 Blocks of different colors sufficient to fill the remainder of the pockets are then placed on the board 2 and the board again agitated until these blocks have entered their respective pockets thereby assembling the 40 blocks, as shown in Figures 1 and 2 of the drawings. A strip of material 11 is then attached to the exposed faces of the assem-

bled blocks, preferably by an adhesive, so that when the strip of blocks is removed from the mounting board the blocks will be 45 retained in their assembled positions and ready to be laid.

Having thus fully described my said invention, what I claim as new and desire to secure by Letters Patent, is:

1. The combination with a mounting board having pockets thereon for the reception of blocks, of means for preventing the entrance of blocks in certain of said pockets.

2. The combination with a mounting board having block receiving pockets thereon, of removable means adapted to be entered in certain of said pockets for preventing the entrance of a block therein.

3. The combination with a mounting board having pockets thereon for the reception of blocks, each pocket having an opening communicating therewith, of an auxiliary board, and means removably attached to 65 said auxiliary board adapted to enter said pockets through said openings for preventing the entrance of blocks in said pockets.

4. The combination with a mounting board having pockets thereon, said pockets having 70 openings communicating therewith, of an auxiliary board, and a plurality of pins removably connected with said board adapted to enter said pockets through said openings for preventing the entrance of a block into 75 any selected pocket.

In witness whereof, I have hereunto set my hand and seal at Anderson, Indiana, this 24th day of January, A. D. nineteen hundred and twenty-two.

HARRY HAUGH. [L.S.]

Witnesses:

Louis S. Jones,

Thomas W. Cranfill.
